UNITED STATES PATENT OFFICE.

HERBERT L. NELKE, OF PHILADELPHIA, PENNSYLVANIA.

FORM FOR SHAPING AND FINISHING GARMENTS.

1,026,451.

Specification of Letters Patent.

Patented May 14, 1912.

Application filed March 15, 1911. Serial No. 614,643.

To all whom it may concern:

Be it known that I, HERBERT L. NELKE, a citizen of the United States, residing in Philadelphia, Pennsylvania, have invented 5 certain Improvements in Forms for Shaping and Finishing Garments, of which the following is a specification.

My invention consists of a form for shaping and finishing garments and is particularly adapted for use in my process of manufacturing knitted combination suits or the like as described in my application for 10 United States patent filed December 14, 1910, Serial No. 597,253.

15 In order to make what is known as a lace bottom or umbrella bottom combination suit, it will be understood that, as the suit is made from a tubular fabric of even diameter, the gussets inserted in the leg portions 20 will have to be extremely large to give the desirable wide flare. Heretofore in manufacturing suits of the above type, the cloth is first steamed in the roll, owing to the cloth being shrunken by the process of bleaching.

25 Various methods and machines are employed for this steaming process. After the cloth is steamed, it is allowed to dry and then cut into lengths. The garment is then cut and shaped and gussets inserted to make 30 the garment finish to desired dimensions and the trimming and sewing completed. The next operation is the finishing, many methods being employed. The one most universally followed is first "rough folding", 35 then "pressing" by means of a mangle or press; then folding preparatory to boxing. Here it will be seen that, as the ironing or pressing will often stretch or shrink some garments more than others owing to the 40 variation in the heat or the way the operator handles them, it is practically impossible to finish a number of garments exactly to a given size and shape and, therefore, there is often uncertainty as to the sizes of the garments in the boxing or packing of the same. 45

The foregoing process is old in the art, and I do not claim the same as my invention.

The chief object of my invention is to produce combination or union suits known 50 as lace or umbrella bottom suits, the leg portions of which will be wide and have an unusual flare, said flared leg portions being formed without the insertion of extra large gussets.

55 Another object of my invention is to make it possible to uniformly finish any number

of garments to a predetermined size and shape.

Another object is to produce a suit of the above type from a piece-bleached fabric 60 made from yarn of uniform thickness and in which the character of stitch is the same throughout the entire fabric.

Still another object is that garments which are finished by the aid of my invention 65 will be narrowed down and shaped at the waist portion, said shaping being accomplished without cutting any goods away or forming a seam.

These objects I attain in the following 70 manner, reference being had to the accompanying drawings, in which:

Figure 1, is an elevational view of a primary form which I employ; Fig. 2, is a view of the main primary form with a 75 garment stretched thereon; Figs. 3 and 4, are elevational views of two stretching or auxiliary forms which I employ; Fig. 5, shows the auxiliary forms within the leg portion of the garment and attached to the 80 primary frame; and Fig. 6, shows the garment after it has been subjected to steaming and drying and the auxiliary forms removed.

Referring to the drawings, 1 is the primary form made in the present instance of non-rustable round wire and shaped at 2, to form leg portions. Transverse reinforcing wires 3, 4 and 5 extend from side to side of the form. The transverse wire 4 has sockets 85 6 and 7 formed therein for the reception of hooks 8 and 9 on the auxiliary forms 10 and 11 respectively. The upper portion of the primary form is indented at 12 to conform to the contour of a person's waist. A 90 socket 13 is formed in the extreme upper portion of the primary form by which the latter may be suspended. The auxiliary forms 10 and 11 have an increasing taper 95 from the bottom to the top. For the purpose 100 of finishing knitted garments as mentioned above I preferably construct the primary form, as shown in Fig. 1, having its dimensions bearing a certain relation to the bleached fabric of the garment and to the 105 fabric before it was bleached. These dimensions are as follows: The width x on the primary form is substantially the same as the width of the unbleached fabric. The width y of the said primary form, and which 110 corresponds to the waist portion of the garment, is less than the width of the un-

bleached fabric but of greater width than the bleached fabric. The combined widths of the bottoms of the auxiliary forms 10 and 11 is decidedly greater than the combined 5 width of the leg portions 2 of the primary form 1.

In the use of my invention: the garments are first slipped over the primary form (as shown in Fig. 2) and the latter is preferably 10 suspended from the socket 13. After the garment has been thus placed upon the primary form the auxiliary forms are placed one within each leg of the garment so that the hooks 8 and 9 engage the sockets 6 and 15 7 in the transverse member of the primary form. The leg portions of the garment are thus stretched to an abnormal width as shown in Fig. 5. The garment, while on the forms can be allowed to remain suspended 20 from the socket 13 for steaming and drying as disclosed in my application for patent Serial No. 597,253 filed December 14th 1910. To remove the garment from the forms, the auxiliary forms are unhooked from the primary form and are allowed to drop from the 25 leg portions as shown in Fig. 6. The entire garment may then be slipped off the primary form.

While my invention is particularly adapted to the manufacture of lace bottom or umbrella bottom suits, it will be understood that it can be used in making a wide sleeve in a sleeved garment or for the production of a wide-flare skirt on a petticoat, etc. 30 35 Also, while I have shown and described the forms as being constructed of non-rustable wire, I may make them of any other material or of a different construction if desirable.

40 While I have described this invention as being particularly adapted for shaping and finishing garments in accordance with my process for which I have made application for patent, the serial number of which is 45 597,253, filed December 14, 1910, where certain portions of the forms are made to have certain specific relations to a bleached fabric

and to a fabric before it is bleached, it will be understood that my invention can be used for shaping, drying and finishing garments of any construction or material. 50

I claim:

1. The combination of a primary form for garments; and a tapered auxiliary form independent of the primary form, said auxiliary form being attached to the primary form with its narrow end adjacent the body portion of the primary form. 55

2. The combination of a primary form for garments having its contour shaped to correspond to the bust, waist and limb portions of a garment; and a plurality of tapered auxiliary forms detachably connected to the primary form with their narrow ends adjacent the junction of the limb portions and body portions of the primary form. 60 65

3. The combination of a primary form comprising a wire frame having a shaped contour corresponding to the bust, waist and limb portions of a garment; means for suspending said primary form; a plurality of tapered auxiliary forms; and means for suspending the auxiliary forms with their narrow ends adjacent the junction of the limb and waist portions of the primary form. 70 75

4. The combination of a primary form, having its contour shaped to correspond to the bust, waist and limb portions of a garment; means whereby the primary form may be suspended; said primary form having a plurality of sockets formed therein; two tapered auxiliary forms, each of said auxiliary forms having a hook adjacent its narrow end; said hooks being adapted to the sockets and forming means whereby the auxiliary forms may be suspended from the primary forms. 80 85

In testimony, whereof, I have signed my name to this specification in the presence of two subscribing witnesses:

HERBERT L. NELKE.
